GLOBOIDAL HOB

Samuel I. Cone, Portsmouth, Va.

Original application May 2, 1927, Serial No. 188,214. Divided and this application July 9, 1930, Serial No. 466,798

9 Claims. (Cl. 29—103)

This is a division of Patent No. 1,885,686, issued November 1, 1932 and relates to cutting tools, and particularly to a hob for cutting teeth in worm wheels and more particularly in worm wheels of the globoidal type.

Theoretically and practically the globoid gear is the most efficient type of worm gear but it has not been extensively used because of the lack of a rational method of generation. The methods of production heretofore in vogue not only were costly but resulted in gear elements of poor mating capacity because the underlying principles were not sound.

The general practice, heretofore, in making the worm wheel has been to use a hob of the form of the globoidal worm, or to use fly-cutters. In the case of the hob the feed is perpendicular to the axes of rotation by advancement either of the hob or of the work piece. Hence, an out-of-time relationship ensues which, obviously, results in the removal of material which should be retained in order to insure proper mating with the complementary worm. The fly-cutter method suffers the disadvantage that it results not only in the removal of material, the presence of which is necessary for true mating capacity, but in that likewise it fails to remove certain material which not only is calculated to but actually results in interference when the wheel and worm are assembled. It is manifest that the profile of the thread of the worm changes at every succeeding section. Hence, a worm wheel produced with a cutter that represents one section of a globoidal worm cannot, in the very nature of things, co-operate properly with the many different profiles of the worm thread. Attempts have been made to alter the worm to conform to the incorrect wheel, but this simply has resulted in the deformation of both.

Evidently, in order to produce a globoidal worm wheel possessed of the maximum contact obtainable, it is necessary to employ an infinite number of cutters. That manifestly is impossible. On the other hand, it is possible and practicable to produce a wheel form having such close approximation to the true theoretical design that the globoidal worm, when later co-operating with the wheel, will produce the theoretically correct form without any perceptible increase in the backlash of the mating members. And the objects of my invention are centered on the attainment of this and, more particularly, in a method of hobbing for generating wheel tooth flanks according to my newly discovered prin-

ciples, whereby there is avoided the disadvantages common to the old established methods.

The nature of the invention consists in producing globoidal worm wheels in such manner that during the entire finishing operation, the 5 predetermined timed relationship is maintained and the active cutting edges of the hob and the wheel blank occupy the same relative positions that the worm and worm wheel eventually will have in service.

The invention further consists in a method of 10 and means for producing precision worm wheels with a hob, whereof the length is such that none of its active cutting edges lie outside the parallel tangents of a certain base circle which may be 15 defined as that produced by extending the flanks of the worm thread inwardly of the wheel when taken in the axis of the worm. In short, the cutting edges of the hob lie and operate within surfaces common in form to those of the thread 20 flanks of the worm with which the wheel is to mate, and under operating conditions the opposed flanks of the hob are, in effect, shifted about its core in such manner as to represent threads thinner than those of the corresponding worm and 25 having a smaller pressure angle but having the property in common with the worm that when its flanks, taken in the axis of the worm, are extended, they become tangent to a common base 30 circle hereinafter more particularly described.

The invention further consists in means for 35 effecting a change in the relative angular positions of the hob and blank during the flank finishing operation in such way as to maintain a fixed relationship between the axes of rotation, 40 thereby maintaining, during the entire flank finishing operation, the same relative positions as regards mating capacity as will later obtain in the finished gear set.

The invention further consists in the method 45 of and means for insuring the production of worm wheels of increased durability and maximum efficiency and whereof the wearing surfaces of the tooth flanks are initially formed by agencies having shaping qualities in consonance with the 48 normal wearing proclivities of the mating worm threads upon said flanks, and whereof the engaging or wearing surfaces of the teeth and threads maintain their relative forms throughout the life of the gear regardless of incidental loss 50 of material or accumulation of backlash.

In the attainment of the objects recited and in accordance with the invention, it is essential that the tooth flanks be formed under conditions analogous to those existing in the wearing of the 55

worm and worm wheel when in operation. This precludes the use of a hob having a body formed identical with that of the worm, inasmuch as the variation of axial distance necessary in feeding the hob into the wheel blank results in the cutting away of considerable material which should not be removed. Hence, one important characteristic of the invention is the forming of tooth flanks in such way as to maintain throughout this 5 operation the same relative positions of the axes of rotation as will later be utilized in the finished gear set. Merely by way of illustration and not as a limitation, it may be said that a simple and efficient way of accomplishing the objects of the invention is to perform the flank shaping operation in two steps; namely, a roughing cut during which the hob and blank are advanced towards each other and then a flank finishing operation during which the axial distance remains fixed 10 and a slight retarding and advancing of the respective positions of the elements causes the hob to seat itself into the right and left flanks of the teeth but, nevertheless, under conditions which preserve the predetermined timed relationship.

15 The invention in its preferred embodiment is illustrated in the accompanying drawings forming a part hereof, wherein:

20 Figure 1 is a plan view of worm and wheel elements having their engaging surfaces formed in accordance with the invention, with parts in section at the midplane to disclose the accurate mating.

25 Fig. 2 is a sectional view on line 2—2—2 of Fig. 1.

30 Fig. 3 is a view taken edgewise of the wheel, Fig. 1, and showing the peculiar tooth characteristic resulting from the new method.

35 Fig. 4 is a view similar to Fig. 1 but with a hob substituted for the worm, and showing the mated fit of the parts at the completion of the first or axial advance step of the cutting operation, some of the hob flutes being omitted to avoid obscurity.

40 Fig. 5 is a view taken edgewise of the wheel, Fig. 4, and showing the tooth characteristic resulting from the first cutting step.

45 Fig. 6 is an end view of the hob form, Fig. 4.

50 Fig. 7 is a plan view of a wheel blank and hob properly mounted for carrying out the invention, portions of the blank and hob being broken away to disclose the mated relation.

55 Fig. 8 is a sectional elevational view of the assembly, Fig. 7.

60 Figs. 9 and 10 are views similar to Fig. 7, showing, respectively, the wheel mounting shifted clockwise and counter-clockwise, the parts in section being in the axial plane of the hob and showing the resulting increase of tooth gap and the reduction of tooth thickness as indicated by the increase of its angle from c to o, the latter corresponding to the angle shown in Fig. 1.

65 Figs. 11 and 12 are, respectively, side and end views of the hob form 6.

Fig. 13 is a side view of hob form 6.

70 Fig. 14 is a view, principally in diagram, showing in a comparative way the development of the tooth from the first or axial advancing step of the hobbing to and including the side cutting step, the completed tooth H, Fig. 3, being indicated in full lines, and the corresponding partly finished tooth J, Fig. 5, being indicated in dash lines.

75 As will appear upon comparison of Figs. 1 and 4, like conditions of relationship obtain during the forming operation as during the actual performance of the worm and its complementary worm wheel in service. In Fig. 1 the circle 1 concentric

with the axis of the wheel is the controlling factor for all flank cutting operation of worms, hobs and wheels, its diameter being determined by the desired tooth angle when taken at the midplane and as indicated at o. It will be observed that the flanks of the teeth are generated so that the line of projection of each flank in the midplane is tangent to the circle aforesaid. It will be also observed that the diameter of the circle also controls the effective length of the worm and in Fig. 4 it will be noted that the hob as to its length, follows the condition stated and that none of its active cutting edges trespass beyond opposing parallel tangents of the base circle. In short, the cutting instrumentalities of the hob are located 10 within and operate within surfaces common in form to those of the thread flanks of the worm with which the wheel is to mate and in which the opposed flanks of the hob are in effect shifted about its core in such manner as to represent 15 threads thinner than those of the corresponding worm.

20 In the pursuance of my inventive thought and while maintaining throughout the complete cycle of forming operations perfect harmony and co-ordination as to timed and fixed center relationship, I preferably accomplish the hobbing in two steps or stages, namely; a roughing cut during which the hob and wheel are advanced toward each other, and a second or flank finishing operation during which the axial distance remains fixed, a slight retarding and advancing of the respective positions of the elements causing the hob to seat itself into the right and left flanks of the teeth and thus maintaining throughout this 30 operation the predetermined time and position relationship. The thread forms of the hob are thinner than those of the worm and this may be accomplished by reducing the angular distance between the opposed flanks of the threads about 40 the hob axis. While the preferential practice is as indicated a two stage hobbing method, the invention is not so limited and the description is simply for illustrative purposes. It will also be but a continuation of my inventive thought 45 to operate on a wheel blank cast with teeth and finished according to my practice.

50 Referring to Fig. 7, the hob 4 is mounted for rotation as at 18 and 19, and the wheel blank 3 is mounted on a rotatable table 17, it being understood that the table and hob spindle are arranged to be driven in proper timed relationship by gearing (not shown) and that means also is provided for advancing the hob spindle with relation to the axis of the table during the 55 first cutting stage. For convenience of illustration one portion of the shaded section shows the hob and wheel blank at the beginning of the first cutting operation and the other portion shows said elements at the close of said operation, the hob spindle having in the meantime advanced through the feed distance n. The blank 3 is mounted on the collar 7 which fits a boss 8 of the table 17 and the counterbore 9 of the blank 3. The blank and collar are secured to the 60 table by means of bolt 10, nut 11, washer 12 and ring clamp 13, the latter fitting counterbore 9' of the wheel blank. The collar 7 is provided with an arm 14 which extends between two studs 15 fixed to the table 17. The studs 15 are tapped to accommodate adjusting screws 16 which lie in a common axis, their points facing each other and engaging opposite sides of the collar arm 14. By releasing the clamping pressure of the nut 11 a slight radial shifting may 75

be given to the collar and wheel in either direction by means of the adjusting screws 16.

The second step of tooth flank correcting or finishing operation involves continuing the running of the hob and wheel as during the first step and at intervals shifting the wheel angularly by means of the adjusting screws 16. It is to be understood that the shifting shown is for the purpose of illustration only and that means other than the parts indicated may be employed for accomplishing the angular shifting of the blank. The slight shifting of the wheel must, of course, be in both right and left directions in turn in order that both sides of opposed tooth flanks may be uniformly finished. Figs. 9 and 10 show the wheel mounting shifted clockwise and counter-clockwise respectively, the shaded portions being taken through the axial plane of the hob and showing the resulting increase of tooth gap and the consequent reduction of tooth thickness as indicated by the increase of its angle from c to o .

The hob forms 4, 5 and 6 are identical except as regards the details of fluting and arrangements of cutting edges, the purpose of which will be presently explained. The hob has a base portion the surface of which is defined by the inner surface of a torus. One or more rows of teeth are disposed on the base portion with cutting edges thereon so disposed that extensions of the cutting edges are tangent to a circle or torus which is concentrically disposed to the said torus defining the surface of the base portion. All of the cutting edges fall within parallel tangents to a circle which is the base circle of the teeth of the worm wheel, the circumference of which corresponds to the torus defining the face of the hob.

The shaded portion of Fig. 4 is a section taken through the midplane of the engaged hob form and wheel and when compared with the corresponding shaded portion of Fig. 1 shows the relationship of the hob thread blank form to that of the worm, the difference being indicated in Fig. 4 by the gap lines of angles c and o . The half angular difference b represents the value 50 of the side shift necessary for each direction in the second or wheel tooth flank finishing step as shown in Figs. 9 and 10. In comparing the hob thread form with that of the worm it will be noted that the angle v represents only 55 a difference in phase at the midplane and does not indicate difference of individual flank form.

Further comparison of the hob thread form with that of the worm may be had by reference to Fig. 2 wherein the inner dash lines and double shading indicate the former and the full lines and single shading indicate the latter. The double shaded or inner form is a section taken on line $t-t$, Fig. 4, when applied to that figure. It will be observed that in Fig. 2 the thread flanks lines 60 of the hob form differ from those of the worm only in position, the shift of each opposed flank about the axis being indicated by the angle w . The ratio of the wheel shift angle v to that of the worm or w is therefore equal to the number 65 of threads in the worm to the number of teeth in the wheel. From this it is apparent that the second or tooth flank finishing step might be accomplished by the introduction of means for relatively advancing and retarding the hob spindle instead of the wheel mounting as shown in 70

Figs. 9 and 10, the angular shift in each direction being w instead of v .

A comparison of the tooth flank form resulting from the first or axial advancing step of the hobbing with that of the second or side cutting step is shown in Fig. 14 in which the completed tooth H, Fig. 3, is indicated in full lines and the corresponding partly finished tooth J, Fig. 5, is shown superposed in dash lines. The regular form of the material removed during the second or fixed axial step is indicated between the arrows at y and z for the right and left flanks respectively, Fig. 14. If a hob having thread form and thickness equivalent to that of the worm had been first fed into the wheel blank 15 the resulting flanks would have the form indicated by the dotted lines and the useful material between the arrows f and g would have been removed, thus initially destroying valuable bearing metal. 20

In making the thin thread hob form the shift value w Fig. 2, is dependent upon the characteristics of the given design and is determined by consideration of the material at f and g as indicated in Fig. 14 the object being to have the 25 thread form narrowed sufficiently to admit of its entry into the proposed tooth gap without removing said material. The designed tooth gap should be also sufficiently wide to admit of the necessary thinning of the hob thread without 30 unduly reducing its face, a reasonable width of which is necessary for the formation of the outer cutting edges 23, Fig. 4. It is also desirable in preparing the hob form to allow a slight fullness of body in order that a root clearance may be 35 provided in the wheel for the worm. This is indicated at e in Fig. 4. The desired end clearance for the teeth of the wheel may be provided by slightly reducing its outer diameter. These clearances have been omitted in the drawings 40 inasmuch as they do not affect the principle in any way and their presence would tend to confusion.

In order to simplify the illustration, the hobs are shown only partly fluted. In Figs. 4, 6, 11, 45 12 and 13 hobs 4, 5 and 6 are shown each of which has its flutes 20 formed in a different manner, the flutes of hobs 4 and 5 being arranged parallel to their axes while hob 6 is grooved spirally. In Figs. 6 and 12 the uncut flutes are 50 indicated by dash lines. The cutting edges are certain of the corners resulting from the intersection of the flutes with the threads and consequently all lie within the thread surfaces. The 55 corners or edges selected are those looking in the direction in which the hob rotates in cutting as 22, 23 and 24, Fig. 4, or 25, 26, 27, Fig. 13.

In order to provide the necessary relief for the cutting edges the thread surfaces in the wake of the edges are slightly sloped or "backed off" 60 as indicated by b in the several views. It will be observed upon reference to Fig. 4 that the thread and flute surfaces intersect obtusely at the edges 22 and acutely at the edges 24. This difference results unfavorably for the cutting 65 qualities of the former edges and favorably for the latter. In the hob 6, Fig. 13, a more satisfactory cutting edge formation results from having the flutes vary in their course in such way 70 as to intersect each thread approximately at right angles to its incidental path, the edges or corners 75 and 27 thus being nearly equal or approximately square. While the latter form of hob possesses superior cutting qualities to those of 75

the straight fluted hob 4, its accurate production is considerably more difficult. By preference hob 4 is used only in the first or axial advance step in which less accuracy is required.

5 The second or finishing step may be performed by the reversing of hob 5, Figs. 11 and 12. In this procedure, and by way of illustration, the first step is performed with the aid of either hob 4 or 6, as shown in Fig. 7 and thereafter substituting hob 5 in the side cutting or finishing operation, Figs. 9 and 10. It will be noted upon inspection of hob 5 that the acute or alternate edge formations only are used, as at 28, 29, the "backing off" in each case being towards 10 the obtuse or rejected edges 30. Inasmuch as this hob is used for side cutting only, its face edges 31 are inactive. It further will be noted that in using this hob a reversal of direction of rotation is necessary for finishing the opposed 15 tooth flanks. The use of hobs, types 4 and 6 is contemplated for both roughing and finishing, and of hob, type 5, for finishing only.

In forming the hob cutting edges care should be observed to have at least one cutting edge 25 within or very near each of the opposed planes of the parallel base circle tangents 21, as at 32, Fig. 11, and 33, Fig. 4; and it also is very important that no active edges be permitted to trespass beyond or outside of said planes. In 30 completing the hob forms shown, all unnecessary material or projections, as indicated at 34, outside of said planes should be removed or reduced in such way as to be non-interfering.

When the word "globoidal" is employed in the 35 claims, it is to be understood to refer to that type of worm gear or tool elements known in the art as enveloping, hour-glass, Hindley, or hollow. These terms distinguish the gear and tool elements from the so-called straight or cylindrical gear and tool elements. In other words, the globoidal worm or hob follows in general the curved periphery of the worm wheel.

When the expression "materially less thickness" is employed in the claims in reference to 45 the teeth of the globoidal hob, it is to be understood as distinguishing such reduction in teeth thickness from that minute reduction in tool dimensions which may be required for effecting clearance between male and female machine parts 50 to permit their interfitting.

Having described the invention, what I claim is:

1. A globoidal hob having arranged thereon at 55 least one row of teeth of materially less thickness than the corresponding globoidal worm thread which mates with the worm wheel cut by said hob.

2. A globoidal hob having arranged thereon at least one row of teeth of materially less thickness than the corresponding globoidal worm thread 60 which mates with the worm wheel cut by said hob and having side cutting edges which are tangent to a circle to which the projection of the flanks of

said worm thread in a plane through the axis of the worm is tangent.

3. A globoidal hob having arranged thereon at least one row of teeth of materially less thickness than the corresponding globoidal worm thread 5 which mates with the worm wheel cut by said hob and having side cutting edges which are tangent to a circle to which the projection of the flanks of said worm thread in a plane through the axis of the worm is tangent, which cutting edges in 10 said plane have an included angle which is less than the included angle between the flanks of said worm thread.

4. A globoidal hob having arranged thereon at least one row of teeth provided with side cutting 15 edges which are tangent to a circle to which the projections on the flank of said worm thread in a plane through the axis of the worm is tangent, said side cutting edges in said plane having an included angle which is less than the included 20 angle between the flanks of said worm thread.

5. A globoidal hob having arranged thereon at least one row of teeth of materially less thickness than the corresponding globoidal worm thread which mates with the worm wheel cut by said 25 hob, said teeth having side cutting edges which in the plane through the axis of the worm have an included angle which is less than the included angle between the flanks of said worm thread.

6. A globoidal hob having arranged thereon at 30 least one row of teeth provided with side cutting edges which in a plane through the axis of the hob have an included angle which is less than the included angle between the flanks of the thread of the worm which mates with the worm wheel 35 cut by the hob.

7. A globoidal hob having arranged thereon at least one row of teeth provided with side cutting edges which are tangent to a circle to which the projections on the flank of said worm thread in 40 a plane through the axis of the worm is tangent, said teeth being so constructed that the cutting edges thereof when extended fall within parallel tangents to said circle when disposed normal to the hob axis.

8. A globoidal hob having arranged thereon at least one row of teeth provided with side cutting edges which are tangent to a circle to which the projections on the flank of said worm thread in a plane through the axis of the worm is tangent, 50 said teeth being relieved in the rear of the cutting edges in such manner that the relieved sides of the teeth when intersected by a plane through the axis of the hob produce lines which when extended are tangent to said circle.

9. A globoidal hob having arranged thereon at least one row of teeth, each tooth having two faces and two sides oppositely disposed, diagonally disposed cutting edges formed between opposite faces and sides, the sides being relieved in opposite directions.

SAMUEL I. CONE.
